Primary Examiner — Barbara Fox*Assistant Examiner* — Messina L Smith(74) *Attorney, Agent, or Firm* — Maginot, Moore & Beck LLP(57) **CLAIM**

The ornamental design for a casket, as shown and described.

DESCRIPTION

FIG. 1 is a perspective view of a casket showing my new design;

FIG. 2 is a front elevational view of the casket of FIG. 1; FIG. 3 is a rear elevational view of the casket of FIG. 1; FIG. 4 is a right side elevational view of the casket of FIG. 1;

FIG. 5 is a left side elevational view of the casket of FIG. 1; FIG. 6 is a top plan view of the casket of FIG. 1; and, FIG. 7 is a bottom plan view of the casket of FIG. 1. The broken lines shown in the drawings illustrate portions of the casket that form no part of the claimed design.

1 Claim, 6 Drawing Sheets(56)
